(57) **CLAIM**

I claim the ornamental design for a load floor latch, as shown and described.

DESCRIPTION

FIG. 1 is a perspective view of the load floor latch of the present invention.

FIG. 2 is a left side view of the load floor latch of FIG. 1.

FIG. 3 is a front view of the load floor latch of FIG. 1.

FIG. 4 is the back view of the load floor latch of FIG. 3.

FIG. 5 is a bottom view of the load floor latch of FIG. 1.

FIG. 6 is a top plan view of the load floor latch of FIG. 1; and,

FIG. 7 is a right side view of the load floor latch of FIG. 1.
